UNITED STATES PATENT OFFICE.

SAMUEL E. HYNDMAN, OF CINCINNATI, OHIO.

CERATE.

SPECIFICATION forming part of Letters Patent No. 238,237, dated March 1, 1881.

Application filed July 24, 1880. (No specimens.)

To all whom it may concern:

Be it known that I, SAMUEL E. HYNDMAN, of Cincinnati, in the county of Hamilton and State of Ohio, have invented a new and useful 5 Improvement in a Preparation to be Placed in Gloves or Mittens for Healing and Whitening the Hands, which improvement is fully set forth in the following specification.

The object of this invention is to prepare a 10 compound which is to be applied to the inside surface of gloves or mittens, so that crack-chaps or sun-burns may be relieved and healed, and also to remove freckles or other local dis- 15 figurations of the hands caused by exposure, as well as to whiten and soften the skin without injury.

I have found by repeated experiments that 20 to apply any form of cosmetics or lotion to the surface of the hand or of the face the ac- 25 tion of the preparation is more effective by excluding the air, so as to secure an even tem- perature, as nearly as possible, and also at the same time to retain at the surface of the skin all moisture due to the preparation. For use on the hand a glove is more effective, since it 30 adapts itself to the hand more readily, and thus more fully answers the requirements.

It is obvious that my preparation is equally 35 well adapted for the face, and a suitable cov- ering applicable for that purpose will be made the subject of a future patent.

The compound consists of the following in- 40 gredients, namely, vaseline, borax, glycerine, and nitrate of potash in the following propor-

tions: vaseline, one ounce; powdered borax, 35 one-half ounce; glycerine, one-fourth ounce; nitrate of potash, two drams.

It is immaterial to the invention how the 40 different ingredients are compounded; but I prefer to first unite the vaseline, glycerine, 45 and potash, and after thoroughly mixing stir in the pulverized borax. The borax is used for its healing properties, and the nitrate of potash to assist in removing tan, &c., while the softening properties of vaseline and glycerine 45 are well known.

The compound thus prepared is intended to 50 be applied to the inside of gloves and mittens, after which they are placed on the hand, and worn during the night or at such other times 55 as may be convenient.

Having described my invention, what I claim 60 as new, and desire to secure by Letters Pat- ent, is—

The within-described compound for healing, 55 whitening, and softening the hands, composed of glycerine, vaseline, pulverized borax, and nitrate of potash, the same to be applied to the inner surface of gloves or mittens, sub- 65 stantially as herein set forth.

In testimony that I claim the foregoing I have hereunto set my hand, this 22d day of July, A. D. 1880, in the presence of witnesses.

SAMUEL E. HYNDMAN.

Witnesses:

J. S. ZERBE,
S. STROBART.
